(57) **CLAIM**

The ornamental design for a “cushion containing gel or compressible material”, as shown and described.

DESCRIPTION

FIG. 1 is a front and top perspective view of the cushion containing gel or compressible material having 4 surface designs of 1.25 sine waves on top and bottom sides.

FIG. 2 is a top view of the cushion of FIG. 1.

FIG. 3 is a bottom view of the cushion of FIG. 1.

FIG. 4 is a edge side view of the cushion of FIG. 1.

FIG. 5 is an edge end view of the cushion of FIG. 1.

FIG. 6 is a top of the cushion containing gel or compressible material as in FIG. 1 except having 2 surface designs of 1.25 sine waves on the top and bottom.

FIG. 7 is an edge end view of the cushion of FIG. 6.

FIG. 8 is a top of the cushion containing gel or compressible material as in FIG. 1 except having 8 surface designs of 1.25 sine waves on the top and bottom; and,

FIG. 9 is a top of the cushion containing gel or compressible material as in FIG. 1 except having 8 surface designs of 1.25 sine waves on the top and bottom.
